UNITED STATES PATENT OFFICE.

CARL BESELER, OF NEW YORK, N. Y.

DESIGN FOR A FRAME FOR AN AIR-COMPRESSOR.

SPECIFICATION forming part of Design No. 15,551, dated November 18, 1884.

Application filed July 3, 1884. Term of patent 7 years.

To all whom it may concern:

Be it known that I, CARL BESELER, of the city, county, and State of New York, have invented and produced a new and original Design for the Main Frame of Hand Air-Compressors, of which the following is a specification.

Reference is to be had to the accompanying drawing, forming part of this specification, in which the figure is a perspective view of the frame of a hand air pump or compressor.

The leading feature of my design consists of an inverted-V-shaped upright braced from or near the apex to give the appearance of a tripod-frame standard or support.

A is the rectangular base, having feet *a a*. B is the inverted-V-shaped upright, consisting of the diverging members *b b*, joined at the top, at which point the upright is enlarged

into the cylindrical portion *c*. The V-shaped upright B rises from the base A, and is braced from a point at or near the enlargement *c* to the base A by the brace C, which consists of the two diverging members *c' c'*, united by the rings, or similar pieces, *d d*.

I claim—

1. The design for a frame for an air compressor or pump, consisting of the inverted-V-shaped upright B and the brace C upon a base, A, as shown.
2. The design for a frame for an air-compressor, consisting of the base A, V-shaped upright B, enlarged at *c*, and the brace C, of diverging members *c' c'* joined by rings *d d*.

CARL BESELER.
